UNITED STATES PATENT OFFICE.

THOMAS LUMSDEN, OF GATESHEAD, ENGLAND.

GRINDING-MACHINE.

1,384,966.

Specification of Letters Patent.

Patented July 19, 1921.

Application filed February 25, 1920. Serial No. 361,220.

To all whom it may concern:

Be it known that I, THOMAS LUMSDEN, a subject of the King of Great Britain and Ireland, residing at Gateshead-on-Tyne, in the county of Durham, England, have invented new and useful Improvements in Grinding-Machines, of which the following is a specification.

This invention relates to grinding machines, and has for its object to provide an improved construction of grinding machine adapted for use in grinding gages and form tools.

A grinding machine in accordance with this invention comprises a bed, parallel guide rods carried thereby, a swinging arm pivotally mounted on one of said guide rods, a grinding wheel and a pointer carried by said swinging arm, means for adjusting said pointer, means for rotating said grinding wheel, means for laterally adjusting said swinging arm, a work table carrying both the blank to be ground and a former or pattern, said work table being mounted on another of said guide rods, means for angularly adjusting said work table, means for giving a fine lateral adjustment thereto, and a spring for returning the swinging arm. In some cases a pointer having a reversed point may be used.

The accompanying drawings illustrate one construction of grinding machine embodying my invention. In the drawings—

Figure 1 is a front elevation; and

Fig. 2 and 3 are elevations looking on the right and left hand sides respectively on Fig. 1.

Fig. 4 is a part side elevation of the lower end of the swinging arm and the guide rod on which it is mounted;

Fig. 5 is a part plan of the work table; and

Fig. 6 is an end elevation of the lower end of the swinging arm and the guide rod on which it is mounted.

Fig. 7 is an elevation of a modified form of the pointer hereinafter referred to;

Fig. 8 is a section of a grinding wheel used for grinding snap gages; and

Fig. 9 is a section of a grinding wheel used for grinding form tools.

Referring to Figs. 1 to 6 of the drawings, the grinding machine therein illustrated comprises a bed 10 which carries in bearings three parallel guide rods, 11, 12, 13 and a countershaft 14. The guide rod 11 is arranged to be moved lengthwise by means of

the handwheel 15 on a shaft 62 on which is also mounted the pinion 16 which engages with an internally toothed wheel 17 on a shaft 18, which is also provided with a pinion 19 engaging a rack 20 on the underside of the guide rod 11. Mounted on the guide rod 11 is a swinging arm 21 which is prevented from moving along the guide rod by two collars 22, 23 (Fig. 4) clamped to the guide rod 11. The swinging arm 21 carries a shaft 24 whereon is mounted the grinding wheel 25. The arm 21 is also provided with a pointer 26 and an operating lever 27. 28 (Fig. 2) is an eye-bolt carried by the arm 21 to which is pivoted a pin 29 carrying a spring 30, said pin passing through a lug 31 on the collar 23 clamped to the guide rod 11. The spring 30 bears against the lug 31 and its tension can be adjusted by means of 70 the wing nut 32 on the end of the pin 29 which is threaded. The spring 30 returns the arm 21 to normal position after it has been swung forward by the operating lever 27. The swinging arm 21 is also provided with a lug 33 (Fig. 6) which is provided with a set screw 34 which co-acts with a fixed lug 35 on the guide rod 11. The set screw 34 forms an adjustable stop for limiting the backward swing of the arm 21. 85

The pointer 26 is carried by a holder 36 mounted on a plate 37 attached to the swinging arm 21 by bolts 38 which pass through slots 39 and allow of vertical adjustment and by bolts 40 which pass through slots 41 and 90 allow of angular adjustment.

On the countershaft 14 is mounted a long pulley 42. The shaft 24 is provided with a pulley 43 (Fig. 1) which is adapted to be driven by the pulley 42 through the belt 44. 95 The counter-shaft 14 is provided with fast and loose pulleys 45, 46 whereby it is adapted to be driven from a convenient source of rotary power.

The guide rod 12 carries a table 47 provided with slots 48 for receiving the usual bolts for holding the work and the former or pattern. The work table 47 is capable of angular adjustment about the guide rod 12 and is clamped in position after adjustment by 100 a locking nut 49 provided with a handle 50 mounted on a screwed part of the guide rod 13, said nut engaging a lug 51 on the table 47 having a curved slot 52 which embraces the guide rod 13. The work table 47 slides on 110 the guide rod 12 and fine lateral adjustment is obtained by means of the guide rod 13.

which is screwed at one end as shown at 53 (Fig. 5). On the screw 53 is a nut 54 working in a casing 55 and restrained against axial movement, said nut being provided with a worm wheel 56 adapted to be rotated by a worm 57 on a vertical shaft 58 provided with a graduated hand wheel 59.

In operation, when it is desired to grind a form tool, a grinding wheel of the type shown in Fig. 9 is substituted for the wheel 25 upon the shaft 24. The blank to be ground and the former or pattern are mounted on the work table 47 so that the pointer 26 engages with the former when the grinding wheel, which is swung forward and held up to the work by the lever 27 against the resistance of the spring 30, engages a corresponding part of the blank, the pointer 26 co-acting with the former insures that the wheel cuts the blank to the desired shape, the wheel and pointer being moved laterally by the hand wheel 15, the blank being thus ground to the shape of the former.

25 When it is desired to grind a snap gage, the gage is first roughly ground to size as above described, using a grinding wheel of the type illustrated in Figs. 1, 2, 3 and 8, and the guide rod 11 is then locked by means of the clamping lever 60 (Figs. 1 and 3) and the work table 47 moved laterally by the worm adjustment operated by the graduated handwheel 59 to grind the gage to the exact finished size.

35 In some cases I may substitute a pointer having a reversed end 61 as shown in Fig. 7 so that the grinding wheel may produce the converse of the former.

What I claim and desire to secure by Letters Patent is:—

40 1. A grinding machine comprising a bed, parallel guide rods carried thereby, a swinging arm pivotally mounted on one of said guide rods, a grinding wheel and a pointer carried by said swinging arm, means for rotating said grinding wheel, means for laterally adjusting said swinging arm, a work table carrying both the blank to be ground and a former, said work table being mounted on another of said guide rods, resilient means normally keeping the grinding wheel away from the blank to be ground, and means for manually swinging the grinding wheel into contact with the blank and holding it there during the grinding operation against the resistance of said resilient means.

45 2. A grinding machine, comprising a bed, parallel guide rods carried thereby, a swinging arm pivotally mounted on one of said guide rods, a grinding wheel and a pointer carried by said swinging arm, means for rotating said grinding wheel, means for laterally adjusting said swinging arm, a work table carrying both the blank to be ground and a former, said work table being mounted on another of said guide rods, a spring for returning the swinging arm, and means for manually swinging the grinding wheel into contact with the blank and holding it there during the grinding operation against the tension of said spring.

50 ground and a former, said work table being mounted on another of said guide rods, means for angularly adjusting said work table, resilient means normally keeping the grinding wheel away from the blank to be ground, and means for manually swinging the grinding wheel into contact with the blank and holding it there during the grinding operation against the resistance of said resilient means.

55 3. A grinding machine comprising a bed, parallel guide rods carried thereby, a swinging arm pivotally mounted on one of said guide rods, a grinding wheel and a pointer carried by said swinging arm, means for rotating said grinding wheel, means for laterally adjusting said swinging arm, a work table carrying both the blank to be ground and a former, said work table being mounted on another of said guide rods, means for angularly adjusting said work table, means for giving a fine lateral adjustment thereto, resilient means normally keeping the grinding wheel away from the blank to be ground, and means for manually swinging the grinding wheel into contact with the blank and holding it there during the grinding operation against the resistance of said resilient means.

60 4. A grinding machine comprising a bed, parallel guide rods carried thereby, a swinging arm pivotally mounted on one of said guide rods, a grinding wheel and a pointer carried by said swinging arm, means for adjusting said pointer, means for rotating said grinding wheel, means for laterally adjusting said swinging arm, a work table carrying both the blank to be ground and a former, said work table being mounted on another of said guide rods, resilient means normally keeping the grinding wheel away from the blank to be ground, and means for manually swinging the grinding wheel into contact with the blank and holding it there during the grinding operation against the resistance of said resilient means.

65 5. A grinding machine comprising a bed, parallel guide rods carried thereby, a swinging arm pivotally mounted on one of said guide rods, a grinding wheel and a pointer carried by said swinging arm, means for rotating said grinding wheel, means for laterally adjusting said swinging arm, a work table carrying both the blank to be ground and a former, said work table being mounted on another of said guide rods, a spring for returning the swinging arm, and means for manually swinging the grinding wheel into contact with the blank and holding it there during the grinding operation against the tension of said spring.

70 In testimony whereof I have signed my name to this specification.

THOMAS LUMSDEN,
